APPARATUS FOR PRINTING WORKS

Willibald Stolle, Freital, Dresden, Germany

Application July 21, 1939, Serial No. 285,756
In Great Britain December 14, 1938

5 Claims. (Cl. 276—44)

This invention relates to an apparatus for printing works for transporting matter to the printing press and dead matter from the press and especially for receiving this dead matter.

5 The invention is intended to overcome the objections inherent to the known method of accommodating the individual matters side by side on correspondingly large letter boards which are difficult to transport and can mostly only be
10 kept on the floor near the printing press and which, after the printing, must be placed in special racks, the matter often collapsing when being shifted from one place to another.

15 The apparatus according to the invention consists of an easily transportable box provided with removable trays and which can be carried in one hand but may also be moved on wheels.

20 The handles are so arranged and constructed that they do not project at the top or sides beyond the walls of the box, so that two or more boxes can be placed one upon the other and consequently several piled up boxes can be wheeled over the floor together or can be fitted together to form a rack.

25 Rollers or preferably balls are fitted on the bottoms of boxes for wheeling them and, when the boxes are piled up, these rollers or balls come to lie within the walls of the box so that the bottom edges of one box rest directly on the upper edges of the other box.

30 Removable trays of zinc, or other suitable material are provided as galleyes for these matters and have side bars which project beyond the end edge which is not bordered, with the result that set up matters can be reliably slipped off the table top on the trays.

35 To prevent the trays from slipping out when the apparatus is being carried, not only the tray rests are inclined downwardly towards the rear but also locking pins are provided which serve at the same time as roller guides for the slipping in of the trays and facilitate their insertion and removal.

40 In spite of the box being open at the front and top simple and practical means are provided to ensure that the interior of the box is kept entirely free from dust, and that the matters are protected against becoming soiled by dust and the like. For this purpose a plate provided with a pleated extension serves as covering for the upper aperture and a plate like a drop slide is provided for closing the front aperture.

45 The surfaces of the slide are preferably treated and each bears one of the list of numbers corresponding to the number of trays, so that notes

concerning the matters actually accommodated may be entered in chalk thereon.

To utilize the whole of the available space or wall surface for the depositing of boxes and difficulties arise when the boxes are piled up and the lower boxes are required, the boxes may be accommodated in racks. As the number of so-called standing matters varies considerably in a short period of time and the mostly restricted space available in printing works make it necessary to frequently change the positions of the racks, fixed racks of a predetermined size are not recommended for depositing the boxes, but racks which can easily be dismantled into their component parts and fitted together in any desired size. These racks consist of base boards with foldable side walls on which an extension piece is placed for forming another compartment.

An embodiment of the invention is illustrated in the accompanying drawing, in which:

Fig. 1 shows a closed box in perspective view,
Fig. 2 is a perspective view of an open box,
Fig. 3 shows a box in longitudinal section,
Fig. 4 shows a tray in perspective view,
Fig. 5 is a perspective view of a rack formed by separate parts with two boxes accommodated therein,

Fig. 6 shows on a larger scale a device for locking a tray in position.

A box, open at the front and top, is formed by a bottom plate 1, side walls 2 and a rear wall 3.

The side walls are connected at the top by stays 4, 5, 6 which are flush with the upper edges of the side walls. These stays serve for stiffening and carrying the box, the middle stay 4 serves for carrying the box with one hand, and the end stays 5 and 6 serve for carrying the box with two hands.

40 The box is closed at the front by a drop slide 7 formed by press board plate and guided in a grooved frame 8. This plate bears a number of numbered sections 9 for noting the contents of the box.

45 The plate has a middle crease 10 so that it can be folded in half.

The box is closed at the top by a plate 11 slideable in a groove and having a pleated extension 12 which enables it to be pushed back out of the way of the plate 7 so that this plate 7 can be lowered into its closing position. The extension 12, however, ensures a tight closure with the plate 7 and prevents the penetration of dust. A flap 13 is also provided on the plate 11, which

can be folded back on to the upper side of the plate 11, when it is desired to remove or to insert the plate 7. When not in use, the plate 7 may be folded on to the plate 11.

- 5   Guides 14 sloping towards the rear of the box are provided in the inner sides of the side walls 2 spaced slightly further apart than the height of the trays serving as galleys. These trays each consist of a plate 15 of zinc, pasteboard, a pressed 10 material or a pressed synthetic composition, on which a three-sided frame 16 is mounted. The ends 17 of the longitudinal laths of the frame project beyond the free edge 18 of plate 15.

Pins 19, which may carry rollers ensure the 15 insertion and removal of the trays with a minimum amount of friction and at the same time lock them against accidentally slipping out as, when the trays have been pushed home in the box, the projecting ends 17 engage behind the 20 pins 19. Consequently, it is necessary to lift a tray before pulling it out of the box. The projecting ends 17 serve at the same time as supports for resting on a table top or the like when slipping a matter on to or off a tray. A bar 20 is fitted on the inner side of the rear wall 3 for the purpose of filling the gap in the box and preventing the matter from dropping therethrough.

Apart from the carrying stays, means are provided for wheeling the boxes. These consist of 30 four rollers 21 mounted on the bottom of the box so that they or their holders form a kind of pin guide inside the stays 5 and 6 and the side walls 2 and thus prevent slipping when two or more boxes are placed one upon the other.

35   As already mentioned, the boxes serve at the same time for storing so-called standing matter. The construction above described also enables several boxes to be piled up; this, however, would necessitate inconvenient manipulation 40 when it is desired to remove the lower boxes of a pile.

Consequently it is proposed to accommodate the boxes in racks whose size is adapted to the actual requirements, and which are built up of 45 separate compartments.

45   Each individual compartment consists of a bottom board 22 on which side walls 23 are hingedly mounted.

The side walls 23 can be folded down flat on to the bottom board 22 and, when constructing a 50 rack they are swung up until stopped by the abutment bars 25. The bottom board 22 has in its under surface transverse grooves 24 in which engage the edges of the raised side walls 23 of a box thereunder.

55   The boxes are prevented from slipping by longitudinal grooves 26 in the upper side of the base plate 22 and in which the runner roller 21 of the boxes engage.

What I claim is:

- 60   1. An apparatus for printing works for accommodating the set up matter before and after the printing comprising boxes equipped with slips in trays serving as galleys and provided with

dust-tight closing means and with means for carrying and wheeling the box, and adapted to be accommodated in racks adapted to be built up in storeys, said boxes consisting of two side walls 5 with slide guides for said trays, a bottom plate and a side wall, and whose open sides are closed the one by a drop slide with numbered sections and the other by a plate provided with a pleated extension and a flap.

2. An apparatus as specified in claim 1 in which 10 the side walls of said boxes are stiffened by cross-stays, which are flush with the upper edges of the side walls and serve as handles, a middle stay serving for carrying the box with one hand and a front stay and a rear stay for carrying the 15 box with two hands.

3. An apparatus as specified in claim 1 in which the boxes are stiffened by cross-stays, which are flush with the upper edges of the side walls, runner rollers on the bottom of the boxes whose 20 mounting serve for anchoring two superposed boxes, each of the trays consists of a plate of zinc, cardboard or synthetic material, on which a three-sided batten frame is fixed whose longitudinal sides project beyond the open edge of the 25 plate.

4. An apparatus as specified in claim 1 in which the boxes are stiffened by cross-stays, runner rollers whose mounting serve for anchoring two superposed boxes, trays on which a three-sided batten frame is fixed, slide guides sloping downwards towards the rear of the box the spacing of said slide guides is greater than the thickness of a tray and frame, at the insertion end 30 of the guides pins or pins carrying rollers serving 35 both as guides for sliding the trays in and out and for locking them against slipping out of the box, a bar fixed on the rear wall of the box, a drop slide being foldable, racks destined to accommodate the boxes and consisting of a plurality of superposed base-boards with two inwardly foldable side walls whose edges engage in cross grooves in the underside of the next higher base-board each box being secured in position by its rollers engaging in longitudinal grooves in the 40 baseboard on which it rests.

5. An apparatus as specified in claim 1 in which the boxes are stiffened by cross-stays, runner rollers on the bottom whose mounting serve for anchoring two superposed boxes trays each 50 consisting of a plate of zinc, on which a three-sided batten frame is fixed, slide guides sloping downwards towards the rear of the box whose spacing is greater than the thickness of a tray and frame, pins or pins carrying rollers are arranged at the 55 insertion end of the guides, which serve both as guides for sliding the trays in and out and for locking them against slipping out of the box, a bar fixed on the rear wall of the box for filling the gap formed by the projecting ends of the 60 frame battens a drop slide being foldable and its surfaces are divided into sections by lines and numbers.

WILIBALD STOLLE.
